Inventor:
Carl F. Pearson
Tone'e Wain Hinkee

UNITED STATES PATENT OFFICE.

CARL F. PEARSON, OF CHICAGO, ILLINOIS.

PUMP.

Application filed April 5, 1922. Serial No. 549,815.

To all whom it may concern:

Be it known that I, CARL F. PEARSON, a citizen of the United States, residing at Chicago, in the county of Cook and State of Illinois, have invented certain new and useful Improvements in Pumps, of which the following is a specification.

This invention relates to improvements in pumps, and has especial reference to improvements in pumps of the rotary piston, sliding blade type.

One of the objects of the invention is, generally, to improve pumps.

Another object is to improve the construction of the piston of pumps, to reduce the expense of manufacture and to facilitate operation thereof.

A further object of the invention is the provision of two pumps and means for connecting them together, in which one pump is adaptable for volume and the other for pressure, or one for pumping air and the other adaptable for moving relatively small quantities of liquid.

The device is especially desirable for use in a spray burner for the combustion of oil in which the oil is atomized or pulverized by a whirling draft of air, the oil being moved by one pump and the air by the other pump, the two pumps being positively connected together, the same relative proportions are maintained throughout all variations of speed at which the pumps are driven.

Other objects and advantages will hereinafter appear from a consideration of the following description when taken in conjunction with the drawings, wherein:

Fig. 1 is an axial section on line 1—1 of Fig. 2.

Fig. 2 is a transverse section on line 2—2 of Fig. 1.

Fig. 3 is a transverse section on line 3—3 of Fig. 1.

In all the views the same reference characters are employed to indicate similar parts.

In the drawings 5 indicates a housing or casing having a cylinder bore 6. The casing member is closed by an end by-plate 7 providing a bearing 8 and a stuffing box 9. In the particular showing the shaft support is shown to have a ball bearing in the hub 10. The plate 11 closes the opposite side 55 of the casing 5 and the parts are held together by the bolts 12 and the nuts 13, the

bolts passing thru the casing and thru the end plates. The end plates and the cylindrical portion of the casing 5 may have ribs 14 extending therefrom to provide a greater 60 surface for contact with the air whereby to carry off accumulated heat due to compression of the air. The hub 15, which is an integral part of the plate 11, is expanded at 16 to provide another housing for a pump 65 17. The pump 17 consists of the housing 16 having a cylinder bore 18 and having ports 19 and 20 connected thru a valve 21 to provide a by-pass between the intake 22 and the discharge 23 of the pump, so that if the resistance which the pumped liquid or fluid encounters is greater than safety would warrant, the valve 24 is automatically lifted against the spring 25 and the liquid will pass from the discharge opening 23 thru the port 70 20, the valve 21, into the port 19, back to the intake opening 22.

A pipe 26 delivers the liquid or fluid from the pump 17 and the pipe 27 communicates with the supply of liquid to be pumped or 80 moved by the pump. A larger pump 28 is provided with a two-part rotating piston sleeve 29 and 30, which contains a cavity 31. The two piston parts are held together by screws 32. The piston sleeve parts 29 and 85 30 each contain two registering slots, 33 on one side of a diametric plane and 34 on the opposite side. These slots are parallel and in them the blades 35 and 36 are reciprocated as the piston is rotated. The composite piston sleeve, 29—30, is eccentric to the cylinder bore 6 and as the piston is rotated the blades 35 and 36 will move inwardly and outwardly of the respective slots. Each of the blades is provided with an arm 90 37 that extends towards the opposite blade and between the arms is an open helical spring 28 that presses the blades outwardly so that their ends contact with the inner surface of the bore 6.

The piston sleeve, 29—30, is rotatable upon a two-part shaft, the part 39 is connected to the piston sleeve part 29, and the part 40 is connected to the piston sleeve part 30. The outer end, 41 of the shaft 40, is reduced and is provided with a slot 42 which engages the pin 43 of the shaft 44 that drives the piston 45 of the smaller pump.

A plate 46 is held on the outer end of the pump 17 and when the plate is removed the 110 piston 45 may be taken freely from the casing or housing 16. On plate 46 is pro-

vided a hollow hub 48 containing a lug 49 pressed against the blades 50 and 51 that are reciprocatable in suitable slots of the piston 45. The hollow hub 48 contains a spring 52 which yieldingly holds the lug 49 in contact with the piston 45 and the reciprocating blades therein.

The pump 28 is provided with an intake opening 54 and a discharge opening 55.

10 From the foregoing description the operation of the pump will be well understood.

While I have herein shown a single embodiment of my invention for the purpose of clear disclosure, it will be manifest to 15 persons skilled in the art, that many changes may be made in the general arrangement and configuration of the parts within the scope of the appended claims.

Having described my invention what I 20 claim as new and desire to secure by Letters Patent, is:—

1. A pump structure comprising a cylinder housing; a hollow rotary sleeve therein eccentric to the axis of the cylinder, said 25 sleeve transversely divided into two members and having a peripheral wall of substantially uniform thickness said sleeve having parallel slots extending therethrough, one on each side of its axis of rotation; means to hold the members together; a blade in each slot; an arm attached to each blade and extending toward the other blade beyond the axis of rotation and wholly within the wall of the sleeve and a spring 30 between the arms to yieldingly hold the blades in outward positions.

2. A pump structure comprising a housing enclosing a cylinder bore; a two-part hollow, rotatable sleeve eccentric to the bore, 40 said parts having registering slots, one on each side of an axial diameter and parallel therewith; means to hold the parts to-

gether; a blade in each slot of the composite piston; an arm extending from each blade toward the other blade, inside the sleeve, 45 and an open helical spring between said arms to yieldingly hold the outer edge of said blades in contact with the inner surface of the housing surrounding the bore, when the composite piston is rotated.

3. A pump structure comprising a housing having a cylinder bore and a rotary piston therein; plates to close the ends of the bore, each plate carrying a shaft support, 50 one said support enlarged at its free end 55 to provide another housing containing a cylinder bore and another rotary piston therein and a shaft connecting both pistons.

4. A pump structure comprising two spaced apart housings; a rotary pump piston in each housing, rotatable about the same axis; an intermediate shaft-bearing expanded at one end to provide one of said 60 housings, supported by said bearing; a two-part shaft and a slip connection for the said 65 shaft parts within said bearing.

5. A piston for a rotary pump comprising a two part sleeve divided centrally of its axis into two cup-shaped members and closed at its ends having two parallel slots 70 extending inwardly, one on each side of its axis of rotation and beyond the axis; a blade reciprocable in each slot; an arm secured to the inner end of each blade extending toward the other blade past said axis 75 and out of the path of either blade; an open compression spring between the arms; means to hold the two parts of the sleeve together and a shaft connected to each part of the sleeve.

In testimony whereof I hereunto subscribe my name.

CARL F. PEARSON.
